UNITED STATES PATENT OFFICE

2,590,071

MEANS FOR PACKING ARTICLES FOR
SHIPMENT

Harry F. Zimmerman, Towson, Md., assignor to
Bendix Aviation Corporation, Towson, Md., a
corporation of Delaware

Application October 14, 1948, Serial No. 54,469

7 Claims. (Cl. 45—22)

1

This invention relates to means for packing articles for shipment in a knock-down condition and particularly to the packing of articles such as tables or the like.

In the television industry the smaller television receivers are of a size which necessitates their support upon a table or similar article of furniture. Some manufacturers market such sets together with supports in the form of tables which may be purchased with the set if the customer desires. These supports are generally in the form of square four-legged tables without tops, the television set fitting downwardly to a certain extent within the square body or frame of the support. The shipping of such supports gives rise to several problems. It is desirable that shipping space be economized. Furthermore, the support is not particularly rigid when set up without a television receiver in place. It is desirable to maintain all portions of each support in one package. It is necessary that the finish be protected against marring both from external contacts and by relative movement of parts of the same support.

It is an object of this invention to provide means for packing such articles and articles of a similar nature in a knock-down form in which the various elements of the article provide mutual support and which protects the article from marring due to contact with outside objects and contact between elements of the article.

It is a further object of the invention to provide, as an article of manufacture, a one piece pad for use in the packing of tables and similar articles in a knock-down form, which pad may be simply made by stamping or die cutting from inexpensive materials.

These objects are attained by the use in each corner of the rectangular upper portion or frame of the support or table, of a packing pad formed from a single piece of cardboard or similar material, the pad having flange-like portions extending over the top and bottom of the corner portion and being provided with two openings for receiving the ends of two legs of the support. The legs are nested within the rectangular portion of the support, two legs being placed along each diagonal with their ends inserted into the holes of the corner pads.

Other objects and advantages of the invention will become apparent from a consideration of the following specification, when taken with the accompanying drawing, in which:

Fig. 1 is a view, in perspective, of a support packed in accordance with the invention;

Fig. 2 is a plan view of a rectangular sheet of

material marked to indicate the cuts and folds to be made in forming a corner pad in accordance with the invention; and

Fig. 3 is a view in perspective showing a corner pad according to the invention, in completed form.

Referring now more particularly to the drawing, Fig. 1 shows a supporting means for a television receiving set or the like; comprising a square or rectangular frame 10 and four, slender, square legs 11. In each corner of the frame 10 is placed a pad 12, which may be formed of cardboard, corrugated paper board, or a similar material. The legs of the support are paired and secured within the frame, each pair of legs extending between opposite corners of the frame and parallel to a respective diagonal thereof. The ends of the legs are secured in the pads 12 in the corners of the frame in a manner to be described.

As more clearly shown in Figs. 2 and 3, each pad 12 is formed by stamping or die cutting from a single rectangular sheet of material which is bent along the lines 14 and 15 to the shape of a C. Near each end of the piece a pointed flap 16 is cut and the corners of the piece are folded back and tucked under the flap as shown in Fig. 3. Abutting one of the lines 14 or 15 and equally spaced from the center line of the piece, rectangular flaps 17 are cut and bent back as shown in Fig. 3, leaving openings 18.

The pad, when completed to the form shown in Fig. 3, is ready for insertion in the corners of the frame 10 in the manner shown in Fig. 1, with the flange portions 18 overlying the top and bottom edges of the frame. In this position the flanges, particularly the thickened pointed portions thereof formed by inserting the corners under the flaps 16, protect the frame against marring from outside contacts, since they act to form a cushion between the frame and its surrounding packing box or crate. The edges of the pointed portions extend outward from the flat sides of the frame and act as cushioning spaces between these sides and the sides of a packing box. Since they are of folded material they are strong enough to withstand the ordinary shocks encountered in shipment without collapsing.

The holes 18 receive the ends of the legs, the legs acting to maintain the pads in place. As the holes 18 are not centered in the pad, but abut one of the lines 14 or 15, they appear near the top or bottom of the frame 10 when the pads are in place. This facilitates the arrangement of the legs so that they do not touch where the two pairs cross at the center of the frame. There are two

possible arrangements of pads to secure this result. In one arrangement the pads coacting with one pair of legs are placed with their holes near the top edge of the frame and the pads coacting with the other pair of legs are arranged with their holes near the bottom edge of the frame. In the other arrangement the two pads coacting with each pair of legs are placed with their holes near opposite edges of the frame. In either arrangement legs of normal size do not touch where they cross.

It will be noted that an article of the type illustrated, when packed in accordance with the invention occupies the least possible space. Furthermore, the parts support each other, yet their finished surfaces do not touch. Also protection against exterior contacts is afforded in every direction.

The invention is applicable to tables with tops, which may be packed in abutting relationship with the frame, with the finished surface of the top preferably turned toward the frame, from which it is cushioned by the flange portions of the pads.

While the invention has been illustrated as applied to a square article, it can also be applied to articles of a rectangular or other form, providing interior points are available within the frame between which the legs may be placed against pads in the manner shown. The invention can be applied to articles of a polygonal form or even to round tables with the pads placed at opposed points of the frame.

While holes are shown formed in the pads to receive the ends of the legs, they may be replaced by indentations or other deformations of the pad material.

What is claimed is:

1. As an article of manufacture, a packing pad comprising a rectangular sheet of self-supporting, deformable material bent along two substantially parallel lines to the shape of the letter C, a flap cut near each end of said sheet with its free end extending toward the adjacent end of the sheet, the corners of said sheet being bent back and inserted under the one of said flaps adjacent thereto, the central portion of said sheet having formed therein a pair of openings, said openings being symmetrically located with respect to the longitudinal center line of said sheet and being adjacent one of said parallel lines.

2. A knocked-down shipping assembly formed from an article which normally comprises an open-ended polygonal frame supported on a plurality of legs: said assembly comprising said frame; padding members located within said frame at opposed corners thereof, each of said padding members embracing the side wall of said frame; and said legs; said legs extending between said opposed corners with their ends secured by said padding members against movement, said legs being in non-touching relation with respect to each other.

3. A knocked-down shipping assembly formed from an article which normally comprises an open-ended continuous sided frame supported on a plurality of legs: said assembly comprising said frame; a plurality of padding members located within said frame at opposing points along the periphery thereof, said members embracing the side walls of said frame at said points; and said legs; said legs extending between said opposed points with their ends secured by said padding members against move-

ment, said legs being in non-touching relation with respect to each other.

4. A knocked-down shipping assembly formed from an article which normally comprises an open-ended rectangular frame supported on four legs: said assembly comprising said frame; a padding member located within said frame at each of said corners, each of said padding members embracing the side wall of said frame; and said legs; said legs extending between said opposed corners with their ends secured by said padding members against movement, said legs being in non-touching relation with respect to each other.

5. A knocked-down shipping assembly formed from an article which normally comprises an open-ended rectangular frame supported on four legs: said assembly comprising said frame; a padding member located within said frame at each of said corners, each of said padding members embracing the side wall of said frame; and said legs; said legs extending in pairs along diagonals of said rectangular frame, the ends of said legs being secured by said padding members against movement, said legs being in non-touching relation with respect to each other.

6. A knocked-down shipping assembly formed from an article which normally comprises an open-ended rectangular frame supported on four legs: said assembly comprising said frame; a padding member located within said frame at each of said corners, said padding members each having a flat central portion terminating at both its ends in a flange, said flanges extending outwardly and embracing the side walls of said frame at the junction of said walls which forms the corner at which said member is located; and said legs; said legs extending in pairs along diagonals of said rectangular frame, the ends of said legs being received in openings formed in said members, said legs being secured thereby against movement and being held in non-touching relation with respect to each other.

7. A knocked-down shipping assembly formed from an article which normally comprises an open-ended polygonal frame supported on a plurality of legs: said assembly comprising said frame; padding members located within said frame at opposed corners thereof, each of said padding members being formed from a rectangular sheet of material with the end portions thereof bent outwardly to form flanges embracing the side walls of said frame at their junction which forms the corner at which said pad is located, the corners of the free ends of said flanges being bent back to shape said ends into a V shape with the sides of the V extending beyond and parallel to the sides of said frame; and said legs; said legs extending between said opposed corners with their ends secured by said padding members against movement, said legs being in non-touching relation with respect to each other.
